UNITED STATES PATENT OFFICE.

WALTER J. BROWN, OF SPRINGFIELD, MASSACHUSETTS, ASSIGNOR OF ONE-HALF TO
JOHN FIRTH, JR., OF SPRINGFIELD, MASSACHUSETTS.

INTERNAL-COMBUSTION ENGINE.

1,144,105.

Specification of Letters Patent. Patented June 22, 1915.

Application filed February 16, 1915. Serial No. 8,502.

To all whom it may concern:

Be it known that I, WALTER J. BROWN, a citizen of the United States of America, residing in the city of Springfield, county of 5 Hampden, and State of Massachusetts, have invented certain new and useful Improvements in Internal-Combustion Engines, of which the following is a specification.

This invention relates to improvements in 10 internal combustion engines, and, more particularly to engines in which oscillatory wing pistons are employed to impart a continuous rotary motion to the crank shaft.

An object of the invention is to provide 15 an improved internal combustion engine with a plurality of wing pistons so assembled and arranged that a minimum of connecting rods and cranks are necessary to connect these pistons with the engine shaft.

Another object of the invention is to provide 20 an improved engine of the class described, wherein the wing pistons are double acting, whereby each piston is the equivalent of two single acting pistons in the ordinary engine.

Another object is to provide an improved 25 engine of the class described, having a plurality of pistons with opposed wings arranged to oscillate between fixed abutments in the cylinder, wherein the spaces between each side of one wing and the abutments are connected, by passages in the piston, with the spaces between the opposite sides of the 30 opposed wing and the abutments. By this arrangement, the explosive energy exerted on one side of one wing is permitted to act as well on the opposite side of the opposed wing, whereby a nicely balanced piston is obtained.

A further object is to provide suitable 40 means, whereby air may be admitted to the space on one side of one wing at the same time that a fuel mixture is admitted to the space on the opposite side of the other wing.

I am aware that the use of oscillatory 45 wing pistons in internal combustion engines is in itself old and shown in the prior art. I am not aware, however, that my improved arrangement, comprising double acting pistons having opposed wings, oscillatory be- 50 tween fixed abutments, and passages connecting the spaces between each side of one wing and the abutments with the spaces between the opposite sides of the other wing

and the abutments, together with means to 55 admit fuel to the space on one side of one wing simultaneously with the admission of air to the space on the opposite side of the other wing has heretofore been used. By such an arrangement, I obtain not only a 60 direct impulse upon one wing due directly to the explosion of the fuel mixture, but also a secondary impulse on the opposed wing due to the expansive effect of the exploded gases on the air admitted to this opposed 65 wing. Moreover, the reduction in compression commonly obtained, when an engine is throttled down is entirely eliminated by these air valves.

In general, my engine comprises a plurality of pistons having opposed wings, which are assembled on a shaft in groups of two, and a crank and connecting rod to connect each group to the engine shaft. One wing of each piston is arranged to be directly 70 acted upon on each side by the explosion of the fuel mixture in the usual four stroke cycle. The opposed wing has each side connected by cored passageways with opposite sides of the other wing and means are provided to admit air to either side of this opposed wing simultaneously with the admission of fuel to the other wing. Thus each piston has one wing directly acted upon by the explosion while the other wing is secondarily acted upon by the expansion of the 75 exploded gases upon the air.

One preferred embodiment of my invention, for the purposes of illustrating one way in which the invention may be carried 80 out is illustrated in the accompanying drawings in which:

Figure 1 is a front elevational view of substantially half of the engine with certain parts broken away to reveal the crank shaft 95 and fly wheel. It is to be understood that to the right of the fly wheel is another portion exactly similar to that shown to the left of the fly wheel; Fig. 2 is a sectional elevation taken on the line 2—2 of Fig. 1; Fig. 100 3 is a sectional elevation of the cylinder taken on the line 3—3 of Fig. 1 looking in the direction of the arrows; Fig. 4 is a sectional elevation of the cylinder taken on the line 4—4 of Fig. 1, looking in the direction of 105 the arrows; Fig. 5 is a sectional plan view taken on the line 5—5 of Fig. 3 looking in the direction of the arrows; Fig. 6 is a sec-

tional plan view taken on the lines 6—6 of Fig. 3 looking in the direction of the arrows; Fig. 7 is a sectional elevation taken on the line 7—7 of Fig. 1 looking in the direction of the arrows. This view is illustrative of the valve operating mechanism; and Fig. 8 is a sectional plan view taken on the line 8—8 of Fig. 7 looking in the direction of the arrows. This view shows half of the 10 valve mechanism for one half of the engine. It is to be understood that the other half not shown is exactly similar and symmetrical with that shown.

Referring to the drawings in detail and 15 particularly to Figs. 1 and 2: 1 represents the cylinder casing and secured to each end thereof are a pair of heads 2. Rotatably mounted in the latter is a shaft 3 and upon this shaft and within the casing 1 are two 20 winged pistons to be later described. These pistons are oscillatory in a curved path and are arranged to move through an angle of substantially ninety degrees. Fixed to one end of the shaft 3 is a crank 12, which is 25 connected by a rod 13 to the crank shaft 14 as clearly shown in Figs. 1 and 2. The latter is suitably mounted in bearings within a crank case 15, which is bolted to the base of the cylinder casing 1. A suitable fly wheel 30 16 is provided on the crank shaft 14 as shown in Fig. 1 and on the other side of the fly wheel 16 is another engine unit identical with that shown to the left of the fly wheel in Fig. 1. It will be seen from Fig. 2 that 35 as the crank 12 oscillates through substantially ninety degrees, a continuous rotary motion is imparted to the crank shaft 14.

Referring to Fig. 5, which shows a sectional plan view of the interior of the casing 40 1, it will be seen that there are two pistons 4 and 4' located between the heads 2 and a central partition in the casing 1. Since both of these units are identical one only will be described and in the drawings, the parts 45 which coöperate with the piston 4' are given the same numerals as similar parts which coöperate with the piston 4, except that these numerals are primed. It will also be seen from Fig. 5 that the piston 4 has two separate cored passages 7 and 8. Fig. 3 clearly shows the passage 7 and Fig. 4 shows the passage 8. Fixed in the walls of the cylinder 1 are abutments 20 between which the wings 5 and 6, integral with the piston 4, 50 are movable. The passage 7 connects the spaces 9 and 10, and the passage 8 the spaces 11 and 19, between the abutments 20 and the wings 5 and 6. On one side of the cylinder 1 and communicating with the space 10, as 55 shown in Figs. 3, 4, and 5, is an exhaust valve 22 and a fuel admission valve 24. On the other side of the cylinder and in communication with the space 11 is an exhaust valve 21 and a fuel admission valve 23.

60 Above these exhaust and admission valves

are air valves (best seen in Fig. 6) there being a valve 26 on one side of the cylinder 1 which communicates by a passage 28 with the space 19 and a similar valve 25 on the other side, which communicates by a passage 27 with the space 9. On both sides of the cylinder and adjacent the admission valves are suitable spark plugs 29 and 30, which may be connected in the usual manner to the customary electrical ignition devices. 70

Fuel is conveyed to both pistons by a single pipe 33 on either side of the cylinder as clearly shown in Figs. 1, 4 and 5. Suitable exhaust pipes 31 and 32 are provided for each piston as shown. Each air valve is located within a housing, such as shown at 34 and 34', and all of these housings are connected by a suitable pipe 35, as clearly shown in Figs. 1 and 2. Within this pipe 35 may be located a throttle or butterfly valve 36 by 80 means of which the amount of air flowing to the valves 25 and 26 may be regulated as desired. Each of the fuel, exhaust and air valves are normally held to their seats by coiled springs as clearly shown in Figs. 2 85 and 6. The fuel and exhaust valves are arranged so that their stems extend vertically downward into the crank case 15 as indicated in Figs. 2 and 7. The air valve 25 is operated by a bell crank 37 pivoted at 38 to 90 a bracket attached to the head 2, and this crank is operated by a rod 39 which is drawn downward at proper intervals by means to be described. The air valve 26 on the other side of the cylinder has a similar lever 40 95 pivoted at 41 and actuated by a rod 42. Thus for each piston 4 there are six valves to be operated viz., two fuel valves, two exhaust valves and two air valves, whose stems are indicated in cross section in Fig. 8 at 100 23, 24; 21, 22; and 39, 42, respectively. The six valves for each piston 4 are actuated from two cams by means, which will now be 105 described. Mounted in parallel relation with the crank shaft 14 is a cam shaft 17, 110 arranged near one side of the crank case 15. This shaft is operated at half the speed of the crank shaft 14 by suitable sprockets and a chain 18. Fixed on the shaft 17 is a fuel admission cam 53 and an exhaust cam 47. 115 Suitably mounted in parallel and spaced relation adjacent the top of the crank case are three rock shafts 43, 44, and 45. Pinned to the end of the shaft 43 is a lever 46 which is forked over and pinned to the air valve operating rod 42. Similarly mounted on the shaft 45 and connected to the other air valve operating rod 39 is a lever 58. Loosely mounted on the shaft 44 is a lever 49 which has a roll bearing directly on the exhaust 120 cam 47. This lever is arranged in substantially horizontal relation and the end thereof is arranged to lift the exhaust valve 22, when the lever is lifted by the cam 47. 125 Loosely mounted upon the shaft 43 is a ver- 130

tically depending lever 48, which passes through an opening in the lever 49 and bears at its end a roll. The latter also bears upon the cam 47 at a point ninety degrees removed from the roll on the lever 49. Connected to the lever 48 is a rod 50, which is connected at its other end to a lever 51. The latter is loosely mounted on the shaft 45 and has a substantially horizontal extension 52, the end of which underlies the stem of the exhaust valve 21. Thus the two exhaust valves are operated by the cam 47. Beyond the cam 47 is an admission cam 53 and directly thereover is a lever 54, which has a depending roll to engage the cam. This lever is pinned to the rock shaft 44 to turn therewith. Adjacent this lever 54 is a depending lever 55 which is also pinned to the shaft 44 to turn, when the lever 54 turns. Secured to the end of this lever 55 is a rod 56, which extends horizontally over the crank shaft 14 and is connected to a lever 57 which is pinned to the shaft 45. Thus when the admission valve 24 is opened by the lever 54 the air valve operated by the rod 39 will also be opened, since the lever 54 turns the shaft 44 and lever 55 and the latter turns the lever 57, shaft 45 and air lever 58, which is pinned to the shaft. Thus, when gas is admitted to the space 10 by the valve 24, air is simultaneously admitted to the space 9 by the valve 25 which is actuated by the rod 39. The other air valve 26, actuated by the rod 42, is similarly opened, when the admission valve 23 is opened, in the following manner. Fixed on the shaft 43 is a vertically depending lever 59, which passes through an opening in the lever 54. This lever 59 has at its end a roll, which also bears on the admission cam 53 at a point ninety degrees removed from the roll on the lever 54. Obviously, this lever, when moved by the cam 53, will turn the shaft 43 and the air lever 46, which is pinned to the shaft 45 as already described. Loosely mounted on the shaft 45 is a lever 62, the end of which underlies the stem of the valve 23. Integral with the lever 62 is a depending arm 61, which is connected by a rod 60 with the cam 50 operated lever 59 just described. Thus, the admission valve 23 and air valve 26 may be simultaneously operated by the cam 53.

It is to be noted that the piston 4 is double acting, as admission and exhaust valves are provided for each side of the wing 6. This wing 6 is reciprocated to and fro between the fixed abutments 20 in the usual four stroke cycle. Thus, in Figs. 3 and 4, the wing 6 is starting to turn counterclockwise to draw a charge of fuel through the valve 24 into the space 10. As this wing 6 turns counterclockwise the burned gases in the space 11 will be expelled therefrom through the exhaust valve 21. On the succeeding clockwise movement of the wing the

charge sucked into the space 10 will be compressed and a charge will be drawn into the space 11. On the next counterclockwise stroke the charge in the space 10 will be ignited from the plug 30 and the charge in the space 11 will be compressed. The return clockwise movement will exhaust the burned gas from the space 10 and the charge in the space 11 will be ignited by the plug 29. Meanwhile, the wing 6' of the piston 4' has been passing through a similar cycle and it is to be noted that at each oscillation of the shaft 3 one charge is being fired so that a continuous torque is applied to the shaft 3. In addition to the positive propulsion of the wing 6, the wing 5 is also propelled by an expansive effect of the explosion of the fuel charge. It will be remembered that, as gas is admitted to the space 10, air is simultaneously admitted to the space 9. Since these spaces are connected by the passage 7, fuel will pass from one side and air from the other side into this passage 7. Near the central portion of the passage 7 the gas and air will undoubtedly blend to some extent but, since the time element is small, there will be little blending except at the point mentioned. The space 9 will be practically all air and the space 10 practically all fuel mixture. On the explosion of the latter the air in the passage 7 and space 9 is violently compressed and expands against the wing 5 to propel the latter in the proper direction. Thus an additional turning movement is obtained to propel the shaft 3 without the use of additional fuel. It is to be noted particularly, that the direct effect of the explosion on one wing and the indirect effect thereof on the opposite side of the other wing, constitute a "couple" since two forces acting in opposite directions through equal arms are provided. Since the shaft is oscillated by means of the couple described, a nicely balanced driving arrangement is provided, wherein lateral strains on the piston are eliminated.

With the arrangement described, four double acting wing pistons are provided, which is the equivalent of eight single acting pistons. With this number of pistons only two connecting rods and two cranks are necessary. Consequently, a considerable saving is obtained through this construction. It is also to be noted, that the air valves also insure a completely filled cylinder. When engines are running, with a highly throttled mixture, the charge drawn in does not fill the cylinder, which leads to a greatly reduced compression. However, with these air valves, the cylinder is filled with sufficient air to replace the reduction in fuel mixture and the compression is undiminished. It should also be noted, that, although in commercial form the engine would undoubtedly be provided with a plu-

rality of pistons as described, a single piston, provided with a fly wheel of sufficient weight, would constitute an operable engine. It is to be recognized that various modifications may be made in the specific structure described without departing from the scope of my invention, which is defined in the appended claims.

What I claim is:

1. In an internal combustion engine of the oscillatory wing type, a cylinder, abutments fixed therein, a piston in said cylinder having opposed wings arranged to oscillate between said abutments, passages formed in said piston extending from each face of one wing to the opposite faces of the other wing, means to admit fuel to either of the spaces between one wing and said abutments, means to admit air to either of the spaces between the other wing and said abutments, whereby one wing may be propelled in either direction by a direct explosive impulse and the other wing may be propelled in either direction by an expansion of said explosive impulse through said passages upon the air, together with suitable exhaust valves and ignition devices, substantially as described.

2. An internal combustion engine, comprising, a cylinder, abutments fixed therein, a plurality of pistons, each thereof having a pair of opposed wings arranged to oscillate between said abutments, means to admit fuel to either of the spaces between one wing of each piston and said abutments, means to admit air to either of the spaces between the other wing of each piston and said abutments, passages formed in each of said pistons extending from each face of one wing to the opposite faces of the other wing, together with suitable exhaust valves, ignition devices and means to operate said valves, whereby one wing of each piston may be propelled in either direction by a direct explosive impulse and the other wing of each piston may be propelled in either direction by an expansion of said explosive impulse through said passages upon the air, substantially as described.

3. An internal combustion engine, comprising in combination, a cylinder, a shaft mounted therein, abutments fixed in said cylinder, a plurality of pistons fixed to said shaft, each thereof having a pair of opposed wings arranged to oscillate between said abutments, passages formed in each piston to connect each side of one wing with the opposite sides of the other wing, means to admit fuel to either of the spaces between one wing of each piston and said abutments, means to admit air to either of the spaces between the other wing of each piston and said abutments, a crank shaft, connecting means between the latter and said piston shaft arranged so that the oscillatory move-

ment of the piston shaft will rotate the crank shaft, together with suitable exhaust valves and ignition devices, substantially as described.

4. The combination in an internal combustion engine, of a cylinder, a shaft rotatably mounted therein, abutments fixed in said cylinder, pistons mounted on said shaft, each thereof having a pair of opposed wings arranged to oscillate between said abutments, a crank shaft, connecting means between the latter and said first named shaft operable to continuously rotate the crank shaft, admission and exhaust valves communicating with the space between each side of one wing of each piston and the abutments, ignition devices for each side of one wing of each piston, air valves communicating with the space between each side of the opposed wing of each piston and the abutments, passages formed in each piston to connect the space between each side of one wing of each piston with the space between the opposite side of the opposed wing and the abutments, and means to operate said valves, said means operable to permit fuel to enter the space on one side of one wing of one piston and air to enter the space on the opposite side of the opposed wing, whereby one wing is subjected to a direct impulse from the explosion of the fuel and the opposed wing is subjected to a secondary impulse from the expansion of the exploded gases upon the air.

5. The combination in an internal combustion engine, of a cylinder, a shaft rotatably mounted therein, abutments fixed in said cylinder, pistons mounted on said shaft, each thereof having opposed wings arranged to oscillate between said abutments, a second shaft and means to continuously rotate it from said first named shaft, fuel admission and exhaust valves communicating with the spaces between each side of one wing of said pistons and said abutments, ignition devices for each side of one wing of said pistons, air valves communicating with the spaces between each side of the opposed wing of said pistons and said abutments, passages to connect the spaces between each side of one wing and the abutments with the spaces between the opposite sides of the opposed wing and the abutments, means to operate said valves, said means arranged so that a fuel admission valve communicating with the space on one side of one wing is opened simultaneously with an air valve communicating with the space on the opposite side of the opposed wing, whereby opposite sides of the opposed wings of one piston may be positively propelled, the one from a direct impulse from the explosion of fuel and the other from a secondary impulse due to an expansive action of said explosion upon the air.

6. In an internal combustion engine, the combination with a casing having a cylin-

drical chamber formed therein, of abutments fixed in said casing and projecting inwardly into said chamber, a piston in said chamber having a pair of wings arranged to oscillate between said abutments, fuel admission and exhaust valves communicating with the spaces between each side of one of said wings and said abutments, ignition devices for each side of one of said wings, air valves communicating with the spaces between each side of the other wing and the abutments, passages formed in said piston to connect the spaces on each side of one wing with the spaces on the opposite sides of the other wing, means to operate said fuel admission and said air valves simultaneously, said means arranged to admit fuel to the space on one side of one wing and air to the space on the opposite side of an opposed wing, whereby one wing may be propelled with a direct impulse from the explosion of said fuel and the other wing may be propelled with a secondary impulse from the expansion of said explosion upon said air, means to operate said exhaust valves, a driven shaft and means to continuously rotate the latter from said piston.

7. An internal combustion engine, comprising, in combination a pair of cylinders, a pair of pistons mounted in each cylinder, a crank shaft, connecting means between each

pair of pistons and said shaft arranged to continuously rotate the latter, abutments fixed in each of said cylinders, each of said pistons comprising a pair of opposed wings arranged to oscillate between said abutments, passages formed in said pistons to connect the spaces between each side of one wing and the abutments with the spaces between the opposite sides of the opposed wing, means to admit fuel to and to exhaust from the spaces on each side of one wing of each piston, ignition means for each side of one wing, means to admit air to the space between each side of the opposed wing and the abutments simultaneously with the admission of fuel to the space between the opposite sides of the other wing and the abutments, whereby each piston is propelled by balanced impulses, one wing being acted upon directly by an explosion of the fuel and the other indirectly through the expansion of the explosion upon air, each of said pistons arranged to operate on a four stroke cycle, whereby four double acting pistons with only two connecting means between said pistons and said crank shaft are provided.
